TABLE

Melbourne F. Smith, Jr., Lenoir, N.C., assignor to Broyhill Furniture Factories, Lenoir, N.C., a partnership

Filed Apr. 15, 1963, Ser. No. 74,420

Term of patent 14 years

(Cl. D33—14)

The dominant features of my new design reside in those portions shown in full solid lines on the drawing.

I claim:

The ornamental design for a table, substantially as shown and described.
